PHOTOGRAPHIC REPRODUCTION APPARATUS

John Paulas, Chatham Township, Morris County, N. J., assignor to Photo Reproducing Equipment Company, Chatham Township, Morris County, N. J.

Application February 16, 1942, Serial No. 431,138

10 Claims. (Cl. 95—73)

My invention relates to photographic apparatus, and more particularly to photographic reproduction apparatus of the type used for making photographic prints by reflex reproduction methods.

One object of my invention is to provide a photographic reproduction apparatus, by means of which clear, sharp positives and negatives can be readily made from objects of any kind.

Another object of my invention is to provide a photographic reproduction apparatus equipped with an illuminating device, which may be for a predetermined period of exposure.

A further object of my invention is to provide a photographic reproduction apparatus having an illuminating device, which may be supplied with current from a network or from a battery.

Another object of my invention is to provide a photographic reproduction apparatus, the main portions of which may be readily taken apart from each other for a convenient storing and carrying around.

My invention consists in certain novel features of a photographic reproduction apparatus as will be fully described hereinafter.

Further objects and advantages of the invention will be apparent from the following description considered in connection with the drawings, in which:

Fig. 1 is a perspective view of a photographic reproduction apparatus according to the invention, a portion of the cabinet being broken away.

Fig. 2 is a cross-sectional view of the apparatus shown in Fig. 1, taken on line 2—2 of Fig. 1.

Fig. 3 is a fragmentary cross-sectional view of the apparatus taken on line 3—3 of Fig. 2 illustrating the time delay switch.

Fig. 4 is a fragmentary front elevational view of the lower left hand portion of the apparatus shown in Fig. 1.

Fig. 5 is an exploded perspective view of parts of the time delay switch.

Fig. 6 is a diagrammatical view of the wiring system of the illuminating device of the apparatus shown in Fig. 1.

Fig. 7 is an elevational view of a different embodiment of a photographic reproduction apparatus according to the invention, a portion of the apparatus being broken away.

Fig. 8 is a sectional view of the casing of the apparatus shown in Fig. 7 containing the illuminating device, taken on line 8—8 of Fig. 7.

Fig. 9 is a sectional view of the casing shown in Fig. 8, taken on line 9—9 of said Fig. 8, and

Fig. 10 is a sectional view of the casing shown

in Fig. 8, taken on line 10—10 of said Fig. 8, the reflector being omitted.

Referring now to Figs. 1 and 2, 20 generally indicates the cabinet of a photographic reproduction apparatus having a cover 22 connected with the cabinet by means of disengageable hinges 24.

A casing 26 for the reception of a supply roll 28 of sensitized paper is mounted on the upper portion of the cabinet 20, and a plate 30 of transparent or translucent material is arranged flush with the upper surface of the casing 26. The plate 30 may be made of a sheet of plate glass painted or sprayed or enameled with white or opal lacquer, for example.

15 The object to be reproduced and a piece of sensitized paper torn off from the end of the supply roll 28 extending through a slot 32 of the casing 26 may be placed in contact with each other upon the plate 30.

20 The underside 34 of the cover 22 has a flexible covering preferably made of felt 36 with a rubber padding 38. The underside 34 is subjected to the action of a plurality of springs 40 arranged inside the cover. When the cover 22 is closed and

25 held in its position by the pull clasps 42, the elements of which are mounted on the outside of the cover and the cabinet, the object and the piece of sensitized paper are tightly pressed against each other by the combined action of the pull clasps 42 and the springs 40.

A base 44 secured to the walls of the cabinet serves to carry the lamp receptacles 46, 48, 50, 52 of the illuminating device arranged below the plate 30.

30 An exchangeable color filter 54 passing through a slot 56 in a wall of the cabinet is slidably arranged on guides 58 between the plate 30 and the illuminating device. The filter 54 may be used, if it is necessary to change the color of the light rays emanating from the bulbs inserted into the lamp receptacles.

A time delay switch 60 for the circuits of the illuminating device is mounted on a false bottom 62 arranged in the cabinet 20.

45 A drawer 64 arranged below the false bottom 62 may be used for storing exposed prints or other articles.

According to Figs. 2 and 6, the illuminating device comprises four sets of lamp receptacles. The set of lamp receptacles 46 serves for the reception of normal incandescent lamps 66 giving off substantially white light; the set of lamp receptacles 48 serves for the reception of photo-flood lamps 68; the set of lamp receptacles 50 serves for the reception of colored lamps 70 giv-

ing off substantially amber colored light; and the set of lamp receptacles 52 serves for the reception of battery lamps 72.

The sets of lamp receptacles 46, 48 and 50 carrying the lamps 66, 68 and 70 are arranged in a circuit 74 comprising an outlet 76 mounted on a side wall of the cabinet for connection with an electric source of high voltage, for example a conventional network. The set of lamp receptacles 52 carrying the lamps 72 is arranged in a circuit 78 supplied with current of low voltage from a battery 80 mounted on the false bottom 62 of the cabinet.

As best shown in Fig. 3, the time delay switch 60 comprises two mercury switches 82 and 84 mechanically coupled with each other. According to Fig. 6, the mercury switch 82 is arranged in the circuit 74, and the mercury switch 84 is arranged in the circuit 78. The mercury switches 82 and 84 are coupled with each other in such a way, that they are simultaneously in opening or closing position.

Furthermore, the circuit 74 comprises a first change-over switch 86 and a second change-over switch 88. The first switch 86 has three terminals 90, 92 and 94. The terminal 90 is connected with the second switch 88, the terminal 92 is connected with the set of photoflood lamps 68, and the terminal 94 is a dead terminal. The terminal 96 of the second switch 88 is connected with the set of lamps 66 giving off a substantially white light, while the terminal 98 of said second switch 88 is connected with the set of colored lamps 70. As will be easily understood from the showing of Fig. 6, depending on the position of the switches 86 and 88 either the set of lamps 66 giving off a substantially white light or the set of colored lamps 70 or the set of photoflood lamps 68 or none of said three sets is connected with the source of electric current of high voltage, when the time delay mercury switch 82 is closed.

The circuit 78 comprises a switch 100 mechanically coupled with the switch 86. The switch 100 has two dead terminals 102 and 104 and a terminal 106 connected with the set of battery lamps 72. The switch 100 is coupled with the switch 86 in such a way, that it may connect the set of battery lamps 72 with the battery 80 only, when the switch 86 contacts the dead terminal 94, i. e. when neither one of the three sets of lamps 66, 68, 70 is connected with a source of current.

The mechanism of the time delay switch 60 is best shown in Figs. 3-5. The two mercury switches 82 and 84 are carried by a support 108 tiltably mounted at 110 on a post 112 secured to the false bottom 62 of the cabinet. An upwardly extending arm 114 of a member 116 tiltably mounted on the post 112 at 118 is in engagement with a fork-like portion 120 of the support 108. A reciprocable controlling lever 122 rotatably mounted on a stud 124 arranged on a post 126 secured to the false bottom 62 is connected with said tiltable member 116 by means of a link 128 slidably passing through a hole 130 of the member 116. One end of said link 128 is pivoted to the controlling lever 122 at 132, the other end of said link has a hook-like portion 134 for engagement with the member 116 when the controlling lever 122 is at a certain distance from the member 116. A spring 136 stretched between the controlling lever 122 and the post 112 tends to hold the lever 122 and the mercury switches 82, 84 connected with said lever in the inactive position shown in Fig. 3. The circuits 74 and 78

comprising the mercury switches 82 and 84 are open in said position of the time delay switch. A spring 138 stretched between the tiltable member 116 and the false bottom 62 tends to turn the member 116 in counter-clockwise direction as viewed in Fig. 3, but the action of the spring 136 is stronger than the action of the spring 138, so that the parts remain in the position shown in Fig. 3 as long as the controlling lever is not actuated.

The reciprocable controlling lever 122 has a slot 140, which is in engagement with a pin 142 secured to a reciprocable rack 144 in mesh with a pinion 146 of a clockwork 148 having a spring 149 and a retarding mechanism 150. The free end of the controlling lever 122 extends through an opening 152 in the wall of the cabinet and through a slot 154 of a plate 156 attached to the outside of the wall of the cabinet. When the controlling lever 122 is depressed against the action of the spring 136, the clock-work is wound up and the member 116 and the support 108 carrying the mercury switches 82 and 84 are tilted by the action of the spring 138, until the switch 82 abuts against the wall of the clock-work and the mercury switches are in the operative position 82', 84' indicated by dash lines. Now, the circuits 74 and 78 are closed. The stroke of the controlling lever 122, however, may be continued and the lever may be depressed further down, for example into the position shown in Fig. 5, as the link 128 may slide through the hole 130 of the member 116 now held in its position. When, after the performance of this stroke, the controlling lever is released, the combined action of the clock-work 148 and the spring 136 return the controlling lever into its initial position. As soon as the controlling lever reaches a position, where-in the hook 134 of the link 128 comes into engagement with the member 116, the member 116 and the support 108 carrying the mercury switches 82, 84 are also returned by the clock-work and the spring 136 into their initial position shown in full lines in Fig. 3, so as to interrupt the circuits 74 and 78. Obviously, the interval of the closure of the circuits 74 and 78 by the operative position of the mercury switches 82 and 84 is controlled by the combined action of the spring 136 and the spring 149 and the retarding mechanism 150 of the clockwork 148 in dependence on the stroke of the controlling lever 122. The greater the stroke of the lever 122, the longer the interval, i. e. the longer the time of exposure of the sensitized paper.

The stroke of the lever 122 may be limited by an adjustable limiting rod 158. The hook-like end 160 of said rod is slidably arranged on the lever 122, and a spring 162 stretched between said hook-like end and the pin 124 tends to draw the limiting rod to the right as viewed in Fig. 3. The free end of the limiting rod extends through the opening 152 of the wall of the cabinet and through the slot 154 of the plate 156. The cylindrical portion 164 of an adjusting knob 166 screwed on the free end of the rod 158 may be inserted into either one of the adjusting recesses 168 of the slot 154. The spring 162 tends to urge the collar 170 of the knob 166 against the plate 156 so as to hold the rod in its position. The knob 166 is in the path of the controlling lever 122 when the latter is depressed, whereby the stroke of the lever 122 is limited. If it is desired to change the stroke of the lever 122 for a change in the time of exposure of the sensitized paper, the limiting rod 158 is drawn

to the left against the action of the spring 162 for disengagement of its cylindrical portion 164 from a recess 168 until the knob reaches the dash and dot line position shown in Fig. 3, whereupon, after the placing of the knob for engagement with a different recess, the limiting rod is released. Preferably, a scale is arranged on the plate 156 next to the recesses 168 indicating various times of exposure so as to facilitate the setting of the desired time of exposure by placing the knob 166 of the limiting rod 158 into the proper recess 168.

According to Figs. 3 and 4, the clock-work 148 is provided with an adjusting lever 172 pivoted at 174 and subjected to the action of a spring 176 tending to hold the lever in the position shown in said figures. The lever 172 extending through the opening 152 of the wall of the cabinet and through a slot 178 of the plate 156 is arranged for influencing the action of the retarding mechanism 150 of the clock-work. If the adjusting lever 172 is depressed against the action of the spring 176, the speed of the clock-work and consequently the speed of the return movement of the controlling lever 122 is increased.

In the embodiment shown in the drawings, the controlling lever 122 of the time delay switch 60 is associated with a clock-work 148 having a spring 149 and a retarding mechanism 150. An actuation of the controlling lever 122 causes a tensioning of the spring 149, and, upon a release of the lever 122, the spring 149 drives the mechanism of the clock-work for returning the lever 122 into its original position under the control of the retarding mechanism; the spring 136 also stretched during the actuation of the lever 122 assists in the returning of the lever. If desired, however, the clock-work 148 may be replaced by a retarding mechanism alone, which has no spring for returning the lever 122 into its original position. In such a case the spring 136 alone would cause the return movement of the lever 122 under the control of the retarding mechanism; in other words, the spring 136 in combination with the retarding mechanism would act like a clock-work.

As best shown in Fig. 1, an indicator 180 preferably made of red glass is inserted into the front wall of the cabinet, so that the user of the apparatus may easily recognize whether or not the lamps of the illuminating device are in operation.

The various sets of lamp receptacles 46, 48, 50, 52 are arranged in such a way on the base 44, that an even distribution of the light emanating from the lamps is obtained. For a better reflection of the light, the inside walls of the cabinet 20 may be painted white and the lamp receptacles may be made of white porcelain.

If desired, one or more sets of lamp receptacles may be omitted, so that, for example, the apparatus has only incandescent lamps giving off a substantially white light and photoflood lamps, or incandescent lamps giving off a substantially white light and battery lamps, or incandescent lamps giving off a substantially white light, photoflood lamps and battery lamps, etc.

According to the embodiment shown in the drawings, the battery 80 is arranged inside the cabinet 20. If desired, however, a suitable outlet could be provided in the circuit 78 for connection with a separate portable battery.

If large objects are to be reproduced, the cover 22 may be taken away from the cabinet by dis-

engaging the parts of the disengageable hinges 24 from each other, so that the large objects may be placed on the plate 30.

Figs. 7-10 illustrate a different embodiment of a photographic reproduction apparatus comprising the three main portions 200, 202 and 204, which may be easily assembled by the user. 200 indicates a four-sided hollow body or stand gradually tapered as it rises and open at both ends. Two opposite walls of the body or stand 200 are provided with flaps 206 foldably arranged at the longitudinal edges of the walls. The two other walls of the body 200 are attached to said flaps by pins 208 or the like. Thus, the walls of the body 200 may be folded upon each other, when the main parts 200, 202, 204 of the apparatus are taken apart, so that the body 200 may be readily stored away in a flat condition. When the apparatus is used, the body 200 is unfolded as shown in Fig. 7 and is placed with its lower end on the plate 202 of transparent or translucent material, such as a plate of glass or plastic material, which fits into the open end of the body 200 and rests on a piece 210 of sensitized paper placed on the object 212 to be reproduced, for example a page of a book. Furthermore, the casing 204 containing the illuminating device is placed onto the edges of the upper end of the body or stand 200.

30 Two batteries 214 and 216 are inserted into holders 218, 220, 222, 224 secured to a wall of the casing 204. The holder 218 is connected with a first terminal 226 of a main switch 228 by a conductor 230, the holder 220 is connected with the holder 224 by a conductor 232, and the holder 222 is connected with a first pole 234 of a lamp receptacle 236 by a conductor 238, as best shown in Fig. 10. The second terminal 240 of the main switch 228 is connected with a first terminal generally indicated by 242 of a time delay switch generally indicated by 244 by means of a conductor 246. The second terminal 248 of the time delay switch is connected with the second pole 250 of the lamp receptacle 236 by a conductor 252.

The first terminal 242 of the time delay switch 244 comprises a resilient base 254 and a contact arm 256 pivotally mounted on said base at 258. One end 260 of said base 254 is secured to a stationary member 262 of the switch attached to a wall of the casing 204 as best shown in Fig. 9. The other end 264 of said resilient base tends to stay away from the member 262 and may be urged toward said member by means of an adjusting lever 266 engaged with said end 264 and pivotally mounted on the member 262. The adjusting lever 266 is held in its position by means of one of the recesses 268 arranged on a curved portion 270 of the member 262.

60 Fig. 9 illustrates the movable contact arm 256 in the operative position, wherein it is in contact with the stationary arm or terminal 248 of the time delay switch for a closing of the electric circuit when the main switch 228 is closed. When the movable contact arm 256 is moved from its inoperative position 256' indicated by dash and dot lines into its operative position by means of a chain 272 attached to the arm, a helical spring 274 wound around the pivot 258 of the arm is tensioned. The free end of the arm 256 contacts an extension 276 secured to the member 262, when the arm 256 is in its end operative position limited by an abutment 278 on the member 262. As soon as the arm 256 is released, the helical spring 274 tends to return

the arm 256 into its inoperative position 256'. This return movement, however, is delayed by the friction between the arm 256 and the extension 276, which in turn depends on the action of the resilient base 252. The more the end 264 of the base 254 is urged toward the member 262 by means of the adjusting lever 266, the smaller the friction between the arm 256 and the extension 276, and the shorter the closing period of the time delay switch. Thus, the time of exposure may be adjusted by the lever 266.

According to the embodiment shown in Figs. 8 and 9, a reflector 280 is arranged around the lamp receptacle 236 carrying the bulb 282.

An exchangeable color filter 286 passing through a slot 288 in the wall of the casing is slidably arranged on a guide 290. The color filter may be inserted into the device or may be taken away therefrom as is required by the reproduction process.

The opening 292 of the casing 204 opposite the bulbs 280, 282 is covered by a plate 294 of transparent or translucent material, for example by a plate of ground glass, which is connected with the wall of the casing in any suitable manner.

Although Fig. 7 illustrates the use of the apparatus for the reproduction of a page of a book, it may be used for the reproduction of any kind of an object, for example letters, documents, tracings, blue prints, etc. Furthermore, the size of the plate 202 may be larger than the size of the lower opening of the body or stand 200; in such case the body or stand 200 is placed on top of the plate 202.

The photographic reproduction apparatus shown in the drawings may be used for the production of positive as well as negative prints by the reflex method of photographic printing.

I have described preferred embodiments of my invention, but it is clear that numerous changes and omissions may be made without departing from the spirit of my invention.

What I claim is:

1. A photographic reproduction apparatus for making photographic prints of an object on a piece of sensitized paper resting on said object, comprising: a casing, illuminating means arranged in said casing, one side of said casing having an opening for the projection of light-rays emanating from said illuminating means, and a hollow stand open at two opposite ends, said casing resting on one of the ends of said hollow stand with said opening facing said end of the stand, and the other end of said stand being arranged for positioning on the piece of sensitized paper so as to press same against the object.

2. A photographic reproduction apparatus for making photographic prints of an object on a piece of sensitized paper resting on said object, comprising: a casing, illuminating means arranged in said casing, one side of said casing having an opening for the projection of light-rays emanating from said illuminating means, and a hollow stand open at two opposite ends, said casing being detachably mounted on one of the ends of said hollow stand with said opening facing said end of the stand, and the other end of said stand being arranged for positioning on the piece of sensitized paper so as to press same against the object.

3. A photographic reproduction apparatus for making photographic prints of an object on a piece of sensitized paper resting on said object, 75

comprising: a casing, illuminating means arranged in said casing, one side of said casing having an opening for the projection of light-rays emanating from said illuminating means, and a hollow stand open at two opposite ends, said hollow stand being foldable, said casing being detachably mounted on one of the ends of said hollow stand with said opening facing said end of the stand, and the other end of said stand being arranged for positioning on the piece of sensitized paper so as to press same against the object.

4. A photographic reproduction apparatus for making photographic prints of an object on a piece of sensitized paper resting on said object, comprising: a casing, illuminating means arranged in said casing, one side of said casing having an opening for the projection of light-rays emanating from said illuminating means, a hollow stand open at two opposite ends, said hollow stand being foldable, said casing being detachably mounted on one of the ends of said hollow stand with said opening facing said end of the stand, and a light-permeable plate arranged at the other end of said stand, and the other end of said stand being arranged for positioning on the piece of sensitized paper so as to press same against the object.

5. A photographic reproduction apparatus for making photographic prints of an object on a piece of sensitized paper resting on said object, comprising: a casing, illuminating means arranged in said casing, one side of said casing having an opening for the projection of light rays emanating from said illuminating means, a hollow stand open at two opposite ends, said casing resting on one of the ends of said hollow stand with said opening facing said end of the stand, the other end of said stand being arranged for positioning on the piece of sensitized paper so as to press same against the object, and a light-permeable plate arranged in the open mouth of said other end of said stand for engagement with said piece of sensitized paper.

6. A photographic reproduction apparatus for making photographic prints of an object on a piece of sensitized paper resting on said object, comprising: a casing, illuminating means arranged in said casing, one side of said casing having an opening for the projection of light rays emanating from said illuminating means, a hollow stand open at two opposite ends, and a light-permeable plate arranged for positioning on the piece of sensitized paper so as to press same against the object, said casing resting on one of the ends of said hollow stand with said opening facing said end of the stand, and the other end of said stand resting on said light-permeable plate.

7. A photographic reproduction apparatus for making photographic prints of an object on a piece of sensitized paper resting on said object, comprising: a casing, illuminating means arranged in said casing, one side of said casing having an opening for the projection of light rays emanating from said illuminating means, and a hollow stand open at two opposite ends, said hollow stand being tapered from its base towards its top, said casing resting on the open top end of said hollow stand with said opening facing said top end of the stand, and the open base of said stand being arranged for positioning on the piece of sensitized paper so as to press same against the object.

8. A photographic reproduction apparatus for

making photographic prints of an object on a piece of sensitized paper resting on said object, comprising: a casing, illuminating means arranged in said casing, one side of said casing having an opening for the projection of light rays emanating from said illuminating means, and a hollow stand open at two opposite ends, said hollow stand being tapered from its base towards its top, said casing being detachably mounted on the open top end of said hollow stand with said opening facing said top end of the stand, and the open base of said stand being arranged for positioning on the piece of sensitized paper so as to press same against the object.

9. A photographic reproduction apparatus for making photographic prints of an object on a piece of sensitized paper resting on said object, comprising: a casing, illuminating means arranged in said casing, one side of said casing having an opening for the projection of light rays emanating from said illuminating means, a color filter slidably arranged in said casing between said illuminating means and said opening, and a hollow stand open at two opposite ends, said hollow stand being tapered from its base towards its top, said casing being detach-

ably mounted on the open top end of said hollow stand with said opening facing said top end of the stand, and the open base of said stand being arranged for positioning on the piece of sensitized paper so as to press same against the object.

10. A photographic reproduction apparatus for making photographic prints of an object on a piece of sensitized paper resting on said object, comprising: a casing, illuminating means arranged in said casing and suitably connected with a circuit, a battery in said casing, a time delay switch in said casing for connecting said battery with said circuit, one side of said casing having an opening for the projection of light rays emanating from said illuminating means, and a hollow stand open at two opposite ends, said hollow stand being tapered from its base towards its top, said casing being detachably mounted on the open top end of said hollow stand with said opening facing said top end of the stand, and the open base of said stand being arranged for positioning on the piece of sensitized paper so as to press same against the object.

25

JOHN PAULAS.
